(57) **CLAIM**

The ornamental design for a bag in box liner container, as shown and described.

DESCRIPTION

FIG. 1 is a forward upper perspective view of a bag in box liner container showing our new design;

FIG. 2 is a rear lower perspective view thereof;

FIG. 3 is a first side view thereof;

FIG. 4 is a rear view thereof;

FIG. 5 is a second side view thereof;

FIG. 6 is a front view thereof;

FIG. 7 is a top view thereof;

FIG. 8 is a bottom view thereof;

FIG. 9 is a second forward upper perspective view thereof, the only difference being the illustration of the upper edges of the bag as unsealed to the box, it being understood that the container is the same as is shown in FIG. 1;

FIG. 10 is a second rear lower perspective view thereof, the only difference being the illustration of the upper edges of the bag as unsealed to the box, it being understood that the container is the same as is shown in FIG. 2;

FIG. 11 is a third side view thereof, the only difference being the illustration of the upper edges of the bag as unsealed to the box, it being understood that the container is the same as is shown in FIG. 3;

FIG. 12 is a second rear view thereof, the only difference being the illustration of the upper edges of the bag as unsealed to the box, it being understood that the container is the same as is shown in FIG. 4;

FIG. 13 is a fourth side view thereof, the only difference being the illustration of the upper edges of the bag as unsealed to the box, it being understood that the container is the same as is shown in FIG. 5;

FIG. 14 is a second front view thereof, the only difference being the illustration of the upper edges of the bag as unsealed to the box, it being understood that the container is the same as is shown in FIG. 6;

FIG. 15 is a second top view thereof, the only difference being the illustration of the upper edges of the bag as unsealed to the box, it being understood that the container is the same as is shown in FIG. 7; and,

FIG. 16 is a second bottom view thereof, the only difference being the illustration of the upper edges of the bag as unsealed to the box, it being understood that the container is the same as is shown in FIG. 8.
